CLIP FOR RADIO FREQUENCY COILS

Paul Ehlert, Berlin, Germany, assignor to Telefunken Gesellschaft für Drahtlose Telegraphie m. b. H., Berlin, Germany, a corporation of Germany

Application October 15, 1938, Serial No. 235,284
In Germany October 15, 1937

4 Claims. (Cl. 173—324)

This invention relates to a new and novel clip for taking off current or voltages at any desired point of a tubular radio frequency coil.

A feature of this invention is the arrangement of a clip which is held against the tubular conductor of the coil by means of contact straps tensioned so as to provide an elastic force.

Radio frequency coils used in large transmitter stations have of late been made frequently of light metal or other tubular parts instead of radio frequency litz or stranded wire. In order that satisfactory electric contact may be made no matter at what point of such a radio frequency tubular coil, it is necessary that the collector or tapping shoe should be pressed against a sufficiently large area of the tubular piece. In the securing means heretofore in use a relatively wide contact band or strap laid around the tubular coil and hooked bilaterally on the fixed part of a tap shoe was tightened by screws designed to pull the mobile part of the contact shoe away from the fixed part and press it against the tube. When this method is used in connection with tubular conductors, there is a risk of causing a permanent change in form or distortion of the tubular radio frequency conductor by unduly firm tightening of the screws, and this should be avoided by all means. When the screws, however, are less strongly tightened so that the above danger is avoided, safe and dependable contact is no longer insured even at temperature changes.

Hence, the problem is to establish at any prescribed places of a tubular radio frequency coil as used in power transmitter stations safe contact even under conditions of heating in routine work, while avoiding permanent deformation of the tubular coil.

According to the invention a split clip strap is used and the holder strip which serves to make connection is rendered yieldable by means of a milled slot. Moreover, screw pressure is not brought to bear directly, but is transmitted rather by way of a spring or a spring packet upon the contact shoe bearing directly upon the coil.

A more detailed description of the invention shall now be given by reference to the appended drawing. Fig. 1 of the drawing shows the tube contact one half in side elevation and half in section. Fig. 2 shows a section taken at right angles to Fig. 1. Referring now in detail to the drawing, 1 denotes the coil tube on which the contact is to be applied. 2 is the holder strip or contact bearing member having a split 3 at its end and flared out to form a T-shaped contact portion serving to tap or take off current or

potential with the contact shoe portion 4. A steel leaf type spring 5 transfers the pressure of the pressure or clamp screw 6 onto the contact shoe 4, on the one hand, and the mobile part 7, on the other hand. Mobile part 7 is provided with two extension ears 1a. Bilaterally hooked on part 7 is the contact strap or band 8 which is brought around the coil tube 1. Band 8 has a slot 8a located on each end through which ears 1a pass. The screws 9 serve solely for holding the assembly together without incidental transmission of any forces thereby. Holding screws 9 are secured to member 4 by being threaded into apertures 9a and are arranged to be freely slidable in the apertures 1b of members 5 and 7. By means of the split 3 it is possible to adapt the contact shoes 4 to any particular form of the coil. The spring 5 insures perfect contact even if as a result of temperature changes or the like slight shifts or variations in size of the coil should have happened.

What is claimed is:

1. An adjustable contact clip for making contact to a conductor of a radio frequency coil comprising a split holder strip forming two contact shoe portions, a pair of contact straps surrounding said shoe portions, each contact strap having a slot located at each end thereof, a pair of movable devices each having engaging means for passing through the slots in each one of said contact straps, said contact straps arranged to pass around a portion of said conductor and the contact shoe portions of said split holder, a spring member interposed between one of said contact shoe portions of said split holder and each movable device, and means to apply pressure between each one of said contact straps and said movable devices to grip said conductor in a spring-like tension contact.

2. An adjustable contact clip for making contact to a conductor of radio frequency coil comprising a split holder strip forming two contact shoe portions, a pair of contact straps surrounding said shoe portions, each contact strap having a slot located at each end thereof, a pair of movable devices each having engaging means for passing through the slots in each one of said contact straps, said contact straps arranged to pass around a portion of said conductor and the contact shoe portions of said split holder, a spring member interposed between one of said contact shoe portions of said split holder and each movable device, and means including a screw which is threaded in said movable devices to apply

pressure between said contact straps and said conductor.

3. An adjustable contact clip for making contact to a conductor of a radio frequency coil comprising a contact bearing element having a T-shaped end, a pair of U-shaped contact straps each one having retention means located at each end thereof, each one of said U-shaped straps located at an end of said T-shaped contact bearing element, a portion of said contact straps arranged to pass around a portion of said conductor, a pair of movable devices each one being slidably secured to said contact bearing element and having means to engage said retention means in said U-shaped contact straps, a spring member interposed between each one of said movable devices and said contact bearing element, and means passing through said movable devices to

apply pressure on said spring member to grip said conductor in a spring-like tension contact.

4. An adjustable contact clip for making contact to a conductor of a radio frequency coil comprising a contact bearing element, a U-shaped contact strap having a slot located at each end thereof, a portion of said contact strap arranged to pass around a portion of said conductor, a movable device slidably supported to a portion of said contact bearing element having engaging means adapted to pass through said slots in said U-shaped contact strap, a flat spring member interposed between said movable device and said contact bearing element, and means passing through said movable device to apply pressure on said spring member to grip said conductor in a spring-like tension contact.
